United States Patent Office.

J. W. BAILEY, OF NEW ORLEANS, LOUISIANA.

Letters Patent No. 75,831, dated March 24, 1868.

TOY-PISTOL.

The Schedule referred to in these Letters Patent and making part of the same.

TO ALL WHOM IT MAY CONCERN:

Be it known that I, J. W. BAILEY, of New Orleans, in the parish of Orleans, and State of Louisiana, have invented a new and useful Improvement in Fire-Cracker Pistol; and I do hereby declare that the following is a full, clear, and exact description thereof, which will enable others skilled in the art to make and use the same, reference being had to the accompanying drawing, forming part of this specification.

This invention relates to a new and improved device for applying the present popular breech-loading principle to the explosion of fire-crackers, whereby the accidents which not unfrequently happen from such explosion are avoided; and the invention consists in mounting a barrel or tube on a stock, and attaching thereto a piece, which acts as a removable breech to the barrel, and also as a trigger, and in providing an aperture, through the barrel at the breech, for the fuse of the fire-cracker, as will hereinafter be described.

The drawing represents a vertical longitudinal section of the pistol.

A is the stock, B is the barrel, and C is the breech-piece. This piece C passes through a mortise, E, in the stock, with its lower end in the form of an ordinary pistol-trigger, and with a flat disk of the diameter of the barrel forming its upper end. Thus formed, the piece C is supported in the mortise E of the stock by a pin, f, as seen in the drawing. In this position it acts the part of a lever, with the pin, f, as a fulcrum. Pulling upon the trigger presses the disk g against the open end of the barrel. In the barrel, at the point marked h, there is a notch, through which the fuse of the fire-cracker is drawn when it is placed in the barrel, as seen in the drawing. The position of the piece C, when it is drawn back for inserting the fire-cracker, is seen in red lines.

What I claim as new, and desire to secure by Letters Patent, is—

The stock A, the barrel B, the piece C, and the pin f, constructed, arranged, and combined substantially as described for the purposes set forth.

J. W. BAILEY.
